UNITED STATES PATENT OFFICE.

CHARLES D. YOUNG, OF ALTOONA, PENNSYLVANIA.

BRAKE-SHOE.

1,119,383.

Specification of Letters Patent.

Patented Dec. 1, 1914.

Application filed April 11, 1913. Serial No. 760,475.

To all whom it may concern:

Be it known that I, CHARLES D. YOUNG, a citizen of the United States, residing at Altoona, in the county of Blair and State 5 of Pennsylvania, have invented certain new and useful Improvements in Brake-Shoes, of which the following is a specification.

The invention relates to brake shoes, and particularly to the provision of a brake shoe 10 having an increased coefficient of friction and better wearing qualities; and the provision of a cast metal shoe having more or less flexibility.

Certain embodiments of the invention are 15 illustrated in the accompanying drawings, wherein—

Figures 1 and 2 are plan and side elevation views respectively of one form of brake shoe, Figs. 3 and 4 are plan and side elevations respectively of a modified type of shoe. 20 Figs. 5 and 6 are plan and partial side elevations of still another modified type of shoe, and Fig. 7 is a section on the line VII—VII of Fig. 6.

Referring to Figs. 1 and 2, the body portion 1 of the shoe is of cast metal, and is provided with the slots 2 and 3 extending inward from the face of the shoe to a point adjacent its back. The back of the shoe is of 25 wrought metal embedded in the cast metal body portion, and comprises a piece of sheet metal in the form of an H, the portions 4, 4, indicated in dotted lines being the legs of the H, and the portion 5 bent up in the form 30 of a lug being the cross bar of the H. This form of back constitutes the subject matter 35 of a copending application Serial No. 760,474, and is not claimed in the present application. In so far as the present invention 40 is concerned, the type of back is immaterial. The slots 2 and 3 are made sufficiently deep so that the end portions of the cast body 1 are flexible with respect to the central portion, and can be sprung slightly 45 with respect thereto. The depth to which these slots extend will vary, depending upon conditions, but are sufficient in all cases to give the shoe the desired amount of flexibility. This feature of flexibility permits 50 the shoe to conform itself more perfectly to the contour of the wheel, thus increasing the

wearing qualities of the shoe. It has also been found that the coefficient of friction between the wheel and a flexible shoe of this character is greater than that in which a 55 non-flexible shoe is used, of the same general construction. The lugs of metal 6 are provided upon the back of the body portion opposite the ends of the slots 2 and 3. These reinforcing lugs 6 serve to strengthen the 60 body portion opposite the slots and prevent the accidental breakage of the shoe before it is applied to the wheel.

The structure of Figs. 3 and 4 corresponds to that of Figs. 1 and 2, in so far as the body 65 portion 1, the slots 2 and 3, and the back, are concerned, but in place of the pairs of reinforcing lugs 6, 6, of Figs. 1 and 2, the single reinforcing lugs 8 are employed, such lugs being located at the center line of the 70 shoe as indicated in Fig. 3.

Figs. 5, 6, and 7 illustrate still another modification, the slots 2² and 3² in the bottom portion 1 being in this case provided not only with the reinforcing lugs on the 75 back of the shoe, but also with the bridging portions 10, 10, so that the shoe is doubly guarded against breakage before its application to the wheel. The reinforcing lugs in this case are in the form of the ridges 9, 9, 80 integral with the body portion and lying opposite the ends of the slots.

What I claim is:

1. In a brake shoe a cast metal body portion having a slot extending inwardly from 85 the face of the body portion to give the body portion flexibility, the said slot terminating short of the back of the body portion, and a reinforcing lug at the back of the body portion opposite the slot and integral with the 90 body portion.

2. In a brake shoe, a cast metal body portion having lugs projecting from its back on either side of the transverse center of the shoe, a reinforcement embedded in the shoe 95 adjacent the back thereof, and means for securing the brake shoe to a brake head, said body portion being provided with a plurality of grooves extending inward from the wearing face substantially to the reinforcement, and disposed opposite the said lugs. 100

3. In a brake shoe, a cast metal body por-

tion having a slot extending inwardly from the face of the body portion and disposed on one side of the transverse center of the shoe, and a reinforcing lug at the back of the body portion opposite the slot and integral with the body portion.

5 In testimony whereof I have hereunto

signed my name in the presence of the two
subscribed witnesses.

CHARLES D. YOUNG.
